FOLDING COUCH BED

Abraham Krakauer, Brooklyn, N. Y., assignor to
 Kay Manufacturing Corporation, Brooklyn,
 N. Y., a corporation of New York

Application February 21, 1940, Serial No. 320,071

8 Claims. (Cl. 5—31)

This invention relates to couch-beds or sofa-beds, and particularly to that type wherein the back-forming part is fixed and the seat part is hingedly mounted for movement into a bed-forming position.

My invention contemplates the provision of a couch-bed wherein a single mattress foldable in half or a pair of separate mattresses are normally concealed within a compartment beneath the seat independently of the back of the couch-bed, and one mattress or mattress part is swingable by a rotary movement into the bed-forming position thereof simultaneously with the automatic lifting to the proper level and forward movement of the other mattress or mattress part.

My invention further contemplates the provision of a couch-bed having a fixed back and a cushioned seat and wherein a mattress and supports therefor are stored in a compartment beneath the seat for extension into a bed whereby the upholstery and cushions of the back and seat respectively are not used for bed purposes and are not subjected to the wear and tear incident to such use, and whereby it becomes possible to use a regular bed mattress instead of makeshift mattresses giving less comfort.

My invention further contemplates the provision of a couch-bed wherein the bed-forming parts are moved by simple and efficient mechanism into their bed-forming positions on manually swinging one of the parts which normally forms the seat from its seat-forming position into its bed-forming position and without the necessity for sliding any parts into or out of the couch-bed.

My invention further contemplates the provision of a radius control bar in the operating mechanism which insures forward movement of the inner mattress frame when the frame is lifted whereby said frame may be folded to a position partly underneath the back of the couch-bed and therefore may be made of a width greater than that of the seat.

The various objects of the invention will be clear from the description which follows and from the drawings, in which:

Fig. 1 is a combined vertical section and end view of a couch-bed to which the invention has been applied.

Fig. 2 is a fragmentary front view of the same, some of the parts being broken away to show part of the operating mechanism.

Fig. 3 is a view similar to Fig. 1 but showing the parts extended into their bed-forming positions.

Fig. 4 is a top plan view of the same on a smaller scale, part of the mattress being broken away to show the mattress frames.

In the practical embodiment of the invention, shown by way of example, the back 10 is fixed to the framework and arms 11 of the couch-bed, the space 12 below and in front of the back and between the arms being utilized as a compartment for storing the mattress parts 13 and 14 as well as the supporting and operating mechanism therefor. Said mattress parts may consist, if desired, of separate mattresses of any suitable type, but are preferably conventional bed mattresses such as inner spring mattresses. The mattress parts may be joined together, as shown, at the adjacent edges thereof if desired to constitute a single suitable folding mattress which may be extended into the position of Fig. 4 wherein there is no space between said parts 13 and 14. A supporting upper frame 15 is provided for the mattress part 13 while a similar lower but wider frame 16 is provided for the wider mattress part 14, said frames being provided with suitable bed springs as 7 of any conventional type suitable for yieldingly supporting the respective mattress parts. The frames are hinged together by means of a suitable hinge comprising the hinge member 17 which is secured to the end rail of the frame 15 and the hinge member 18 similarly secured to the end rail of the frame 16, said hinge members being pivotally connected as by means of the hinge pin 19.

It will be understood that a hinge, such as above described is provided at each of the two front end corners of the frames 15 and 16 and that the operating mechanisms for the frames, soon to be described, at both ends of said frames are substantially identical, so that a description of one such mechanism will suffice for both. To prevent the frames 15 and 16 from collapsing upon each other in the folded or inoperative positions thereof and when the mattress parts 13 and 14 have been removed from the compartment 12, an L-shaped member 20 preferably of angle iron has one end thereof as 21 connected to the frame 15 at its rear end (Fig. 1) and at its front end is connected to the hinge member 17 as at 22. A similar L-shaped member 23 is secured in reversed position with one end as 24 thereof secured to the frame 16 and the other end 25 secured to the hinge member 18. The horizontal flanges of said members 20 and 23 rest upon each other when the frames are folded into the positions of Fig. 1 and by maintaining said frames in spaced relation, provide sufficient space between the

frames for the reception of the mattress parts 13, 14.

Preferably removable cushions as 26 are supported by the upper frame 15 and form the seat of the couch-bed. It will be understood however that the upper surface of the frame 15 may be upholstered to provide a fixed or permanent seat instead of removable cushions in a manner which will be readily understood and hence needs no further description. The weight put upon the seat 26 is transmitted through the frame 15, which forms the direct supporting member of the seat, and the members 20 and 23 to the frame 16 and thence to the supporting frame of the couch-bed by the supporting and operating mechanism soon to be described.

The front panel of the couch-bed forms the front wall of the compartment 12 and normally conceals the frames and the mattresses. Said panel consists of the fixed rail 27 extending between the arms 11, and the movable rail 28 hinged to the fixed rail by means of suitable hinges as 29. The rails are suitably upholstered at their front or visible faces. The rail 28 is automatically swung out of the way of the frame 16 when said frame together with its hinge member 18 is lifted (Fig. 3). This is accomplished by the movement of the link 30, which is pivoted at one end to the hinge member 18 and at its other end to the bracket 31 projecting rearwardly from the rail.

Extending between the fixed front rail 27 and the fixed rear rail 32 is the frame support or transverse rail 33 preferably of angle iron, and which is provided with terminal strap hangers at 34, 35 secured to the respective front and rear rails and suspending the support 33 therefrom. A pair of spaced slots 36, 37 are made in the support, the slot 36 receiving the pin 38 of the roller 39 secured by a suitable bracket to the lower end of the leg 40. Similarly, the slot 37 receives the pin of the roller 41 at the lower end of the leg 42. Said legs 40 and 41 cross each other at 43 where they are pivotally connected. The pin 44 at the upper end of the leg 42 slides in the slot 45 in the end member of the frame 16, while the upper end of the leg 40 is pivoted to said end member by the pin 46. Preferably, the rollers 39 and 41 normally transmit the weights of the frames 15, 16, and of the mattress parts 13, 14, and of a person sitting on the seat 26, to the horizontal flange of the support 33, while permitting the frame 16 and its mattress to be easily lifted and collapsed.

It will be noted that when the frame 16 is lifted, it is also moved forwardly to carry the rear edge part thereof out of the space underneath the back 10. To insure such forward as well as upward movement, the radius control bar 47 is provided. Said bar is pivoted at its lower end as by the pivot 48 to the support 33 and by the pivot 49 at its upper end to the end member of the frame 16. As shown in Fig. 1, the bar 47 is in a substantially horizontal position when the parts are collapsed or folded inside of the compartment 12, the legs 40 and 42 are also collapsed about the pivot 43, the front rail 28 is vertical, the member 20 rests upon the member 23, the rear edge portion of the frame 16 together with its mattress part 14 are below and partly underneath the back 10, and the mattress part 13 is folded upon the mattress part 14 and rests thereon. An extensible and foldable leg 50 for supporting the frame 15 when said frame is in its extended position, is also folded into parallel relation with said frame.

Said leg is pivoted as by the pin 51 to said frame 15, and is automatically operated by the links 52 and 53 when the frame is swung on its pivot 19. The link 52, at one end, is pivoted as at 56 to the one end of the leg 50, and at its other end to the link 53. The upper end of the said link 53 is pivoted as at 54 to the hinge member 17, the lower end of said link being secured to the pin 44 operating in the slot 45. The connecting pivot 55 for the links 52 and 53 is normally to the left of the pivot 54, as viewed in Fig. 1.

To extend the frames into the bed-forming positions thereof from the position of Fig. 1, the seat cushions 26 are first removed, if said cushions are loose cushions. The seat frame 15 is then rotated about the pivot 19 into the position of Figs. 3 and 4 causing automatic operation of the other parts. That is, the pivot 54 is rotated with the hinge member 17 to a point above the pivot 19, thereby raising the link 53 and exerting an upward pressure on the frame 16 to raise said frame. The control bar 47, however, controls the movement of the frame 16 and instead of permitting it to rise vertically under the pull of the link 53, imparts a forward as well as a rising movement to said frame sufficient to carry the rear edge portion of the frame end of the mattress part 14 resting thereon out of the space directly beneath the back 10 to easily clear the back. As the frame 16 rises, the legs 40 and 42 are extended and the rollers 39 and 41 move to the right hand ends of the respective slots 36 and 37 (Fig. 3).

As the hinge member 18 rises, the lower end of the link 30, as viewed in Fig. 1, is also raised and the movable rail 28 swung about its hinges 29, the forward movement of said hinge member also aiding to swing the rail until it assumes the position thereof shown in Fig. 3, wherein it is out of the way of the raised frame 16. Furthermore, during the rotation of the frame 15 into the position of Fig. 3, the pivot 55 of the link 52 is carried on the other side or to the right of the pivot 54, thereby lowering the pivot 56 at the other end of the link and rotating the leg 50 about the pivot 51 into the extended position thereof shown in Fig. 3, wherein said leg serves to support the frame 15 in its bed-forming position. The mattress part 14 may now be rotated onto the frame 15 to be supported thereby or it may be rotated simultaneously with the rotation of the frame as described.

It will be noted that by utilizing the space underneath the back 10, the frame 16 may be made substantially wider than the frame 15 and wider than the seat of the couch-bed, so that when the frames are extended to provide a bed, the width of the resulting bed is more than twice that of the seat 26; and that by the mechanism just described, which imparts a forward as well as a lifting movement to said frame 16, it becomes possible to extend the parts without interference with the back.

It will further be seen that by the mechanism employed for operating the frames, none of the surface upholstery is subjected to any wear when the couch-bed is used as a bed, and that an adequate conventional bed mattress may at all times be stored between the frames in readiness for immediate use when the frames are extended.

While I have shown and described certain specific embodiments of my invention, I do not intend to be understood as limiting myself thereto, but desire to claim my invention as broadly as may be permitted by the state of the prior art and the scope of the appended claims.

I claim:

1. In a couch-bed having a relatively fixed back, a pair of frames hinged together and foldable into a seat-forming position wherein one frame is above the other and both frames are below and in front of the back, a mechanism to lift the lower frame and to move said lower frame forwardly on the rotation of the upper frame through an angle of approximately 180°, said mechanism including a radius control bar pivoted at one end to a relatively fixed point of the couch in front of and below the back and pivoted at its other end to said lower frame, a pair of crossed legs each pivoted at its upper end to the lower frame, fixed means on the couch for supporting the lower ends of the legs, and a link bar connected at one end to the upper end of one of the legs and to the lower frame and operatively connected at its other end to the upper frame and movable therewith.

2. In a couch-bed having a compartment therein, a pair of frames, a pair of hinge members each connected to one of the frames and hingedly securing said frames together at adjacent ends of the frames for movement into a bed-forming position wherein said frames are substantially coplanar, said frames being normally foldable into said compartment into a seat-forming position wherein one frame is above the other and providing a mattress-receiving space therebetween when so folded, means operatively connecting the frames to lift the lower frame when the upper frame is rotated forwardly into its bed-forming position, said means comprising a bar pivoted at one end to the hinge member for the upper frame and a pair of crossed legs each pivoted at its upper end to the lower frame and one of said legs being also pivoted to the other end of said bar, and means for imparting a forward movement to the lower frame simultaneously with the lifting of said lower frame including a radius control bar pivoted at one end to the lower frame and pivoted at its other end to a relatively fixed part of the couch.

3. In a couch-bed, a pair of frames, a hinge pivotally connecting said frames, means for lifting one of the frames on the rotation of the other frame about the pivot of the hinge comprising a first bar pivoted to the hinge adjacent said other frame, a pair of crossed supporting legs for said one frame each pivoted at its upper end to said one frame, one of said legs being also pivoted to the first bar, means for imparting a forward movement to said one frame on the lifting thereof comprising a radius control bar pivoted to the lower frame and to a relatively fixed part of the couch, a pivoted leg on said other frame, and a second bar connecting an end of the leg to the first bar to extend said leg automatically on the rotation of said other frame about the pivot of the hinge.

4. In a couch-bed, a relatively fixed back, a pair of frames foldable one into vertically spaced relation to the other and with part of the lower frame underneath the back, said lower frame being wider than the upper frame, a leg pivoted to the upper frame, a pair of crossed legs pivoted at their upper ends to the lower frame, and means for simultaneously lifting the lower frame and imparting a forward movement thereto on the rotation of the upper frame relatively to the lower frame, said means including a radius control member pivoted to the lower frame and to a relatively fixed point of the couch-bed, and a pair of bars operatively connected to each other

and to the legs of the respective frames, one end of that bar connected to the legs of the lower frame being operatively connected to and movable with the upper frame.

5. In a couch-bed, a pair of mattress-supporting frames, a hinge connecting the frames for relative rotation thereof into a seat-forming position wherein one frame is above the other and into a bed-forming position wherein said frames are substantially coplanar, a pair of crossed legs pivoted at their upper ends to the lower frame, a third leg pivoted intermediate its ends to the upper frame, and means for simultaneously extending the legs of the frames and for lifting and imparting a forward movement to the lower frame on the rotation of the upper frame, said means comprising a pair of bars, one operatively connected to the other and also connected to an end part of the third leg and the other bar connected to the hinge and to the upper end of one leg of the pair of legs, and a radius control bar pivoted to the lower frame and to a relatively fixed point of the couch-bed, a hingedly supported front rail, and means for swinging said rail out of the path of the lower frame on the rotation of the upper frame.

6. In a couch-bed having a fixed back, a pair of frames foldable relatively to the back into a seat-forming position wherein one of the frames is above the other and into a bed-forming position wherein the frames are substantially coplanar, a hinge comprising a pair of pivoted hinge members, one connected to the front part of one of the frames and the other to an adjacent part of the other frame, the lower frame being wider than the upper frame and extending underneath the back in the seat-forming position thereof, a pair of mattress parts normally arranged between the frames in the folded positions of the frames, a fixed transverse supporting rail in the couch-bed extending from a point below the back to the front of the couch, a fixed front rail, a second front rail hinged to the fixed front rail, a pair of crossed supporting legs pivoted to and supporting the lower frame and having their lower ends movable on the transverse rail, means operatively connecting one of the hinge members to the second front rail to swing said second rail on the movement of the frames toward and from the bed-forming positions thereof, a bar operatively connecting the other hinge member to the lower frame and to the upper end of one of said crossed legs to raise said lower frame on the movement of the upper frame to the bed-forming position thereof, and a control bar pivoted at one end to the lower frame and at the other end to the transverse rail, said bar imparting forward movement to the lower frame on the movement of the upper frame out of its folded position.

7. In a folding bed couch, a pair of mattress supporting frames one foldable over the other to form a seat, a hinge pivotally connecting the frames and comprising a pair of hinge members each pivoted to the other at corresponding ends thereof and each fixed to one of the frames at the other end thereof, and an L-shaped spacing member for each frame, each fixed to one of the hinge members at the end of the longer leg thereof and fixed to one of the frames at the end of the shorter leg thereof, the longer legs of said spacing members being adapted to rest on each other in the seat-forming positions of said frames wherein one frame is in vertical spaced relation

to the other, whereby weight put upon the upper frame is transmitted to the lower frame.

3. In a folding bed couch, a pair of mattress supporting frames, a hinge hingedly securing said frames together, a spacing member for the end of each frame having a normally horizontal rail and a normally vertical rail, the horizontal rail being secured to the hinge and the vertical

5 rail being secured to the frame, said members maintaining the frames in vertical spaced relation and the horizontal rails thereof being in contact when the frames are folded about the hinge into a position wherein one frame is over the other.

ABRAHAM KRAKAUER.
